Fowson & Fowson

UNITED STATES PATENT OFFICE.

ARTHUR C. ROWLEY, OF PHILADELPHIA, PENNSYLVANIA, ASSIGNOR TO GLOBE
AUTOMATIC SPRINKLER COMPANY, OF PHILADELPHIA, PENNSYLVANIA, A
CORPORATION OF PENNSYLVANIA.

CAP FOR HOSE CONNECTIONS.

1,404,895.

Specification of Letters Patent. Patented Jan. 31, 1922.

Application filed September 23, 1920. Serial No. 412,183.

To all whom it may concern:

Be it known that I, ARTHUR C. ROWLEY, a citizen of the United States, residing in Philadelphia, Pennsylvania, have invented
5 Caps for Hose Connections, of which the following is a specification.

This invention relates to removable closures for so-called "steamer" or hose pipes, such as are provided at the bases of office, 10 factory and other buildings equipped with fire extinguishing systems, and one of its objects is to provide a relatively simple device for removably retaining a cap in place on such a pipe or connection so as to prevent the accidental or malicious placing 15 therein of solid bodies such as might obstruct the flow of water.

Another object of the invention is to provide a device for normally holding a cap on 20 a hose connection so as to prevent its too easy removal, which while being relatively simple and substantial in construction, shall be of such design as to facilitate its quick removal by a person having the necessary 25 knowledge and apparatus.

The invention further contemplates a novel form of retaining strap and frangible lug for normally holding a cap in position over the otherwise open end of a pipe 30 such as a hose connection.

These objects and other advantageous ends I attain as hereinafter set forth, reference being had to the accompanying drawings, in which,

35 Fig. 1 is a side elevation, partly in vertical section, illustrating the end of the coupling member of a hose connection having my invention applied thereto; and

40 Fig. 2 is a plan of the construction shown in Fig. 1.

In the above drawings, 1 represents a substantially cylindrical casting in the form of a coupling sleeve such as is customarily mounted on the end of a steamer or hose 45 connection. This sleeve is provided with two oppositely placed projecting cylindrical lugs 2 and is internally threaded at 3 for the reception of the correspondingly threaded end of a length of hose. For closing the otherwise open end of this sleeve I provide a circular plate 4, preferably having an internally projecting annular rib 5 for centering it on the sleeve 1, and including a pair of T-shaped lugs 6 projecting

from its edge at opposite points thereof so 55 as to extend downwardly along the side of the said sleeve. These T-shaped lugs are joined to the body of the cap 4 by relatively thin neck portions 7, preferably notched as indicated at 8 to facilitate their easy breakage and each having projecting upwardly from the center of its top edge or face an extension 8, which, since the top of said lug is substantially flush with the top surface of the cap 4, may easily be struck by a hammer or other tool when it is desired to break the lug free from the cap. The latter is of course made of a material, usually cast iron, which is capable of such breakage.

The two oppositely projecting arms of 70 each of the T-shaped lugs 6 extend substantially parallel with and are spaced away from straight portions of the adjacent edge of the cap 4, defining slots adjacent which the top face of said cap is formed with relatively shallow, substantially rectangular recesses or depressions 9. These latter are designed to receive the bent over ends 10 of a metallic strap 11, whose central portion is curved around one of the projecting lugs 2 80 of the sleeve 1 and whose side members extend between the latter and the cross arms of the lugs 6 through the slots 12, above which they are turned at right angles so as to lie within said recesses 9.

The straps 11 are made of more or less 85 springy, non-corrodible metal and after the cap 4 has been centered by its rib 5 on the sleeve 1, are forced or bent into their proper positions, the central part of each strap extending around one of the cylindrical lugs 2 and its ends projecting through the slots 12 and then into the recesses 9.

When it is desired to quickly detach or remove the cap 4 from the sleeve 1, it is only 95 necessary to strike the extensions 8 of the T-headed lugs 6, whereupon the necks 7 break, usually in vertical planes passing through the slots 8, thus freeing the straps 11 and permitting said cap to drop off. A 100 water supply hose may thereupon be made, with the certainty that there will be no obstruction in the line of pipe connected to the sleeve 1, such as might interfere with the flow of water.

105 I claim:

1. A cap for a hose connection consisting of a plate having projecting lugs connected

to it through relatively frangible necks, each of said lugs having an upward extension to facilitate its breakage from the plate.

2. A closure for a hose connection consisting of a plate having lugs projecting from its edges and each including oppositely extending portions spaced away from the plate to provide slots.

3. A closure for a hose connection consisting of a plate having lugs projecting from its edges and each including oppositely extending portions spaced away from the plate to provide two slots, there being recesses formed in the plate adjacent said slots respectively.

4. A closure for a hose connection consisting of a plate having substantially T-shaped lugs connected to it by frangible necks, the top arms of each of the lugs being spaced away from the edge of the plate.

5. A closure for a hose connection consisting of a plate having substantially T-shaped lugs connected to it by frangible necks, formed with their upper parts spaced away from the edge of the plate; with an upwardly projecting extension from the top of each of said lugs to facilitate its breakage.

6. The combination of a hose connection having projecting lugs; with a plate closing the end of said hose connection having lugs

connected to it by frangible necks and each separated from said plate by two relatively narrow slots; with straps each having its body extended around one of the lugs of the hose connection and its ends extended through the slots onto the top face of the plate.

7. The combination of a tubular structure having projecting lugs; a plate closing the end of said structure and having two substantially T-shaped lugs connected to it by frangible necks; with straps having their ends at right angles to their side portions and projected over the plate, the side portions of each of said straps extending respectively between the plate and the arms of one of the lugs thereof and passing around the lugs of the tubular structure.

8. The combination of a tubular structure having projecting lugs; a plate closing the end of said structure and having two substantially T-shaped lugs connected to it by frangible necks; with straps each having its ends at right angles to its side portions and projected over the plate, the side portions of each strap extending respectively between the plate and lugs and passing around the lugs of the structure; with upward extensions from each of the plate lugs.

ARTHUR C. ROWLEY.
